LOUIS WILPUTTE, OF NEW ROCHELLE, NEW YORK, ASSIGNOR OF TWO-THIRDS TO ALICE A. WILPUTTE, OF NEW ROCHELLE, NEW YORK.

COKE-OVEN IRON WORK.

1,320,432.

Specification of Letters Patent.

Patented Nov. 4, 1919.

Application filed May 27, 1918. Serial No. 236,712.

To all whom it may concern:

Be it known that I, LOUIS WILPUTTE, a subject of the King of Great Britain, and a resident of New Rochelle, county of Westchester, in the State of New York, have invented certain new and useful Improvements in Coke-Oven Iron Work, for which the following is a true and exact description, reference being had to the accompanying drawings, which form a part thereof.

My present invention relates to the construction of coke ovens and comprises improvements in the iron frame work or sectionalized armor commonly applied to the sides of by-product coke ovens having horizontally elongated coking chambers running transversely to the length of the battery, with door closed ends at the opposite sides of the battery.

The general object of the invention is to provide a simple and effective frame work which will facilitate the operation of luting (sealing with clay) the joints at the margins of the removable doors closing the ends of the coking chambers, and which tend to insure joint luting of a desirable form, and to minimize the evil effects on the iron work and oven structure of such failure of the joint seals as may be expected to occur from time to time in regular operation.

The various features of novelty which characterize my invention are pointed out with particularity in the claims annexed to and forming a part of this specification. For a better understanding of my invention, however, and the advantages possessed by it, reference should be had to the accompanying drawings and descriptive matter in which I have illustrated and described a preferred embodiment of my invention.

Of the drawings:

Figure 1 is a side elevation of a portion of a coke oven battery in which my invention is employed.

Fig. 2 is a partial section on the line 2-2 of Fig. 1.

Fig. 3 is a section taken similarly to Fig. 2 through one of the flash plates adjacent the end of the battery.

Fig. 4 is a partial section taken on the line 4-4 of Fig. 1.

Fig. 5 is a plan view of a portion of the oven frame work.

Fig. 6 is an elevation of a portion of the apparatus shown in Fig. 5, and

Fig. 7 is a sectional elevation of a portion of the iron work, the section being taken similarly to Fig. 4, but on a larger scale, and showing only a portion of the apparatus appearing in Fig. 4.

In the oven construction illustrated in the drawings, A represents the masonry oven structure proper which is formed with alternate horizontally elongated coking chambers A', and intervening flue heating walls A². The ends of the coking chambers are normally closed by doors D, each of which comprises a metallic frame work D', and a body D² of fire brick. At its sides each door is provided with ribs or flanges D³, which project beyond the margin of the door proper and abut against portions C' of metallic parts C commonly called flash plates, which cover the ends of the hollow heating walls A² and are interposed between the masonry of the oven structure and the vertical beams or buck stays B and B', which form major parts of the metallic frame work or armor of the battery. The two buck stays B and B' in front of each heating wall are connected together by cross braces B², and the buck stays at the opposite ends of the heating wall are tied together by metallic tie rods running transversely to the length of the battery.

In so far as above mentioned, the construction shown does not differ from construction well known and in general use. The flash plates C, as shown, differ from those heretofore used in that they are formed at their edges with outwardly projecting lips or ribs C². The ribs or lips C² are shown as forming outer extensions of transverse flanges which also extend outwardly from the flash plate bodies, and at their inner edges, are offset in the usual manner at C' to provide seats for the inner sides of the flanges D³ of the door. Preferably the transverse flanges of the flash plates and the ribs D³ of the door are shaped and proportioned to provide a comparatively narrow but deep tapered groove or channel at each side of the door in which the luting or joint sealing material H is packed. The luting material H is ordinarily formed by clay applied while in a moistened mortar like condition.

The provision of the lips C^2 insures a luting channel deep enough to receive the proper amount of luting material and involves an economy in the use of the luting material inasmuch as they form an effective check against the tendency of the workmen applying the luting material to plaster the latter over a portion of the flat outer face of the flash plates C , which is commonly experienced with the construction heretofore employed in which the flash plates are not provided with the lips C^2 . The reduction in the amount of luting material necessary to secure good joint seals, made possible by the use of the present invention, is of value in that it reduces the labor required for the luting operation, and reduces the amount of the baked luting clay to be removed in breaking the joints and preparing them for sealing when the coke is discharged from the oven chambers and the latter are thereafter charged with coal. An even more important advantage obtained by the use of the flash plate lip C^2 arises from the fact that when the luting joints fail, as they frequently do in use from the baking and cracking of the clay as the coking operation proceeds, the issuing gas which ignites as it enters the atmosphere, is prevented by the ribs C^2 from working along the face of the flash plate, so that the gas flames do not come in contact with the adjacent buck stays. The impingement against the buck stays of the flames resulting from the combustion of the gas issuing through cracks in the luting material itself, or other joint opening between the dried luting material and the adjacent flash plate surfaces, which is avoided with the present invention, has been a frequent source of injury to the buck stays of coke ovens as heretofore constructed. With the present arrangement the gas flames, resulting from leaks through the sealing material, can do comparatively little damage, and moreover the cracks themselves may be easily located and closed, when serious, by the application of fresh luting material.

Advantageously, the pair of flash plates C , at the opposite sides of each coking chamber, are connected in an oven of the type illustrated by a metallic part or lintel E above the coking chamber and forming the top portion of the door frame. Preferably the lintel parts should be connected to the flash plates by joints having sufficient flexibility or capacity for lost motion to accommodate the relative movements of the two flash plates at the opposite sides of a coking chamber resulting from the thermal expansion of the oven structure. The flexibility or lost motion thus permitted should not be great enough, however, to permit any substantial movement of a lintel member relative to the other parts of a door frame under the forces to which it is subjected in

the operation of removing and replacing the corresponding coke oven door. The somewhat contradictory conditions are well met by the special construction illustrated in which each lintel comprises a body portion, which, in the assembled condition of the apparatus, lies in the plane of the lips C' of the adjacent flash plates, and comprises pintle-like portions E^5 at opposite ends, which are received in notches C^4 formed in the edges of the adjacent flash plate lips C' . Each part E is also formed with lugs E^6 , which bear against the inner face of the corresponding flash plate lips C' when the parts are assembled. The notches C^4 of the flash plates and the pintle extensions E^5 of the members E are so proportioned that the members E may be swung into and out of place as indicated in Fig. 7. The oven masonry is recessed as indicated at A^4 to receive the body portion of the member E , and being further recessed as shown at A^3 to receive the lugs E^6 and an inner stiffening flange or rib E^7 formed at the bottom of each member E . Each member E also comprises a portion E^2 outwardly inclined from the body portion of the member and forming the upper wall of a luting channel provided between the member E and the rib or outwardly extending lip D^4 at the top of the metallic portion of the corresponding door D . Each member E is formed, as shown, with lugs E^8 at the back of the inclined portion E^2 of the member, and each lug is notched as indicated at E^4 to receive a locking bar F , the ends of which are also received in notches C^6 formed in the transverse flanges of the corresponding flash plates C , the adjacent notches E^4 and C^6 registering when the member E is in its normal position. Each flash plate is formed with an inclined portion C^5 , which may be regarded as an outturned portion of the corresponding flash plate lip C' , and these flash plate portions C^5 lie in the same plane with the portions E^2 of the member E in the assembled condition of the apparatus. Advantageously as shown appreciable clearance is provided between the vertical and top edges of the notches C^4 and the adjacent edges of the member E and between the latter and the registering edges of the flash plates above the notches C^4 to give the desired joint flexibility. After each member E is put in place and secured by the corresponding bar F , the portion of the recess A^4 above the member A is filled with moist clay or other similar luting material H' . The material H' is, of course, broken away and replaced by fresh material whenever a member E is replaced. The clay H' prevents gas leakage out of the oven chambers along the members E .

The members E contribute to the formation of desirable joint seals at the top of

the door, and the manner in which they are detachably secured in place minimizes breakage resulting from the expansion of the oven, and minimizes the difficulty of effecting replacements of this portion of the armor in case breakage of the parts, or necessity for other repairs, makes removal and replacement of the members E desirable. Those skilled in the art will understand that the expansion of the oven parts may cause appreciable relative movements of the two flash plates C at opposite sides of the coking chamber. For instance on the expansion of the oven brick work the flash plate at one side of an oven door may move up with the upper portion of the brick work with which it is in contact for an inch or so while the other flash plate may not lift at all or may move to an appreciably smaller extent. The expansion of the oven may also cause a greater outward movement of the upper end of one flash plate than of an adjoining flash plate. With the described method of connecting the lintel members to the flash plates such relative movements of the upper ends of the flash plates may occur without resulting in any breakage of the flash plates, lintels or connecting means. It will be understood of course by those skilled in the art that after the initial heating up of the ovens is completed and thereafter from time to time as required the recess A⁴ is repacked with clay to eliminate gas leakage and to more or less firmly anchor the lintel member in place though not holding the lintel in place with sufficient rigidity and strength to cause breakage on normal subsequent relative movements of the upper ends of the flash plates. The flash plates CA adjacent the ends of the battery are made with a single transverse flange with lips C' and C² at but one side. It will be understood, of course, that the flash plate CA, shown in Fig. 3, is for use at the left hand end of the side of the battery shown in the drawings, and that a flash plate differing therefrom only in having its door frame edge reversed is employed at the opposite end of the same side of the battery.

While in accordance with the provisions of the statutes I have illustrated and described the best form of my invention now known to me, it will be apparent to those skilled in the art that changes may be made in the form of the apparatus disclosed without departing from the spirit of my invention set forth in the appended claims, and that certain features of my invention may sometimes be used with advantage without a corresponding use of other features.

Having now described my invention, what I claim as new and desire to secure by Letters Patent, is:

1. In a coking oven having horizontal open ended coking chambers, removable

doors entering and closing the ends of said chambers and a metallic frame work comprising vertical buck stays and flash plates interposed between the buck stays and the masonry sides of the oven structure, and forming the sides of the frames for doors closing the ends of the coking chambers, the improvement which consists in lips on the flash plates projecting outwardly from the faces of the latter between the doorways and the adjacent buck stays and uniting with the adjacent door surfaces to form grooves adapted to receive joint luting material.

2. In a coke oven of the type having horizontal open ended coking chambers and a metallic frame work at the sides of the battery and forming the sides of the frames for the doors closing the ends of the coking chambers, the improvement which consists in metallic door and frame work parts uniting to form grooves at the sides of the doors adapted to receive joint luting material and having their outer edges projecting beyond the adjacent portions of said frame work.

3. A flash plate adapted for use between the vertical buck stays and the adjacent end of a hollow heating wall of a horizontal retort coke oven and formed with a transverse flange at each edge which projects inwardly from the flash plate and is inturned at its inner edge, and also projects outwardly from the outer face of the flash plate.

4. In a horizontal retort coke oven, the combination with the flash plates at the opposite sides of the retorts at the ends of the latter, of metal connecting members located above the coking retort, said members and flash plates being formed with coöperating parts uniting to form a hinge connection between the members and the flash plates, and means for detachably securing said parts together.

5. In a horizontal retort coke oven, the combination with the oven masonry and the flash plates at the opposite sides of the retorts at the ends of the latter, of metal connecting members located above the coking retort, said members and flash plates being formed with coöperating parts uniting to form a hinge connection between the members and the flash plates, means for detachably securing said parts together, the oven masonry being recessed to receive said members and plaster inserted in said recesses about said members.

6. In the metallic frame work of a horizontal retort coke oven, the combination with flash plates at the opposite sides of each coking chamber formed with notches C⁴ in their adjacent edges, of a metal flash plate connecting member formed with extensions E⁵ entering the notches C⁴ and forming hinge connections between said member and the adjacent flash plates, and also formed with portions E⁶ adapted to bear against

115

120

inner surfaces of the flash plates, and means for detachably securing said member and flash plates together.

7. In the metallic frame work of a horizontal retort coke oven, the combination with flash plates at the opposite sides of each coking chamber formed with notches C⁴ on their adjacent edges, of a metal flash plate connecting member formed with extensions E⁵ entering the notches C⁴ and forming hinge connections between said member and the flash plates, and also formed with portions E⁶ adapted to bear against inner surfaces of the flash plate, and a locking bar F

for detachably securing said member and 15 flash plates together, said parts and flash plates being formed with notches receiving said locking bar.

8. In a horizontal retort coke oven the combination with flash plates at the opposite 20 sides of a retort at one end of the latter of a metallic lintel member at the top of the retort and connected to said flash plates by joints flexible to accommodate the relative movements of the flash plates resulting from 25 the thermal expansion of the oven.

LOUIS WILPUTTE.
